UNITED STATES PATENT OFFICE.

ROBERT A. FORESMAN, OF MOORES, PENNSYLVANIA, ASSIGNOR TO WESTINGHOUSE ELECTRIC AND MANUFACTURING COMPANY, A CORPORATION OF PENNSYLVANIA.

STOKER CONSTRUCTION.

Application filed April 9, 1923. Serial No. 630,986.

My invention relates to multiple retort underfeed stokers and it has for its object to provide a stoker of the character designated which shall have a high efficiency of 5 overload ratings. A further object of my invention is to provide in an underfeed stoker, in which rows of tuyères and fuel-feeding retorts are alternately arranged in parallel relation and inclined downwardly 10 from the front toward the rear of the furnace, for a more complete combustion of fuel at the lower end of the underfeed stoker grate. A still further object of my invention is to provide in a multiple retort underfeed stoker furnace a retort which shall 15 be of generally decreasing depth from front to rear and which shall have the rear portion of the retort bottom composed of one or more tuyère plates or members.

These and other objects, which are more manifest in the further description of my invention, may be attained by the employment of the apparatus illustrated in the accompanying drawings, in which Fig. 1 is a 20 view in longitudinal section of a portion of an underfeed stoker grate embodying my invention; Figs. 2 and 3 are fragmentary views in transverse section of the apparatus illustrated in Fig. 1, taken on the lines 25 II-II and III-III, respectively, of that figure; Fig. 4 is a fragmentary plan view of the rear of the underfeed grate; Fig. 5 is a fragmentary view in elevation of the 30 rear end of the underfeed grate; Fig. 6 is a fragmentary view in section through the 35 lower end of the tuyère bank; and Fig. 7 is a fragmentary view in section of a modified form of the lower end of the retort shown in Fig. 1.

Referring to the drawing for a detailed description of the embodiment of my invention herein illustrated, I show an underfeed stoker having inclined banks of tuyères 10 and alternately disposed retorts 11. Ram boxes 13 are disposed at the forward ends 40 of the retorts in such manner that fuel from hoppers 14 is fed into the several retorts 11 by reciprocating rams 15. A suitable refuse-discharging mechanism 16 is pro-

vided at the rear of the grate and may be 50 in the form of an oscillating air-feeding grate, as shown. The above described structures are conventional in stokers of the multiple retort type and since the specific structures of the feeding and discharging mechanism form no part of the present invention, a detailed description thereof is deemed unnecessary for the purposes of the present application. It is to be understood, furthermore, that other specific feeding and discharging mechanisms may be employed with the apparatus of the present invention.

Each of the retorts 11 consists of two angle irons 12 secured at the rear and lower ends to a member 14 which in turn is secured to an I-beam 15, and carried at their upper ends in slots 16 of a member 17 which is bolted to an I-beam 18. Side retort plates 19 are carried by the angle irons 12, to which they are secured as by bolts 20, and are further supported by projections 14' of the member 14 at their lower ends, and by castings 21 disposed above and secured to the member 17 at their upper ends. The side plates 19 are provided with laterally extending ribs 22 which are inclined with respect to the angle irons 12 and upon which the bottom plates 23 are disposed to form retorts of decreasing depth from front to rear. Side plates 19 have at their upper edges 70 flanges 24 upon which the tuyère plates 10 are carried.

The bottom plates 23 of the retorts terminate short of the rear ends of the retorts, as shown in Fig. 1, and the bottoms of the 75 retorts are continued to the rear edge of the grate by means of one or more tuyère plates 25, disposed in each retort and supported on ribs 26 integrally formed in the retort side plates 19. The ribs 26 are notched, as at 27, 80 for engagement with cooperating lugs 28 on the tuyère plates 25. The tuyère plates 25 are similar to the tuyère plates employed in the tuyère banks 10, with the exception that they have but a slightly curved front 85 edge and the air discharge ports therein are designed to direct air rearwardly and horizontally through the lower ends of the re-

torts into the fuel bed. Dead plates 30 engage at their lower ends the retort sides at 31 and are carried at the rear by the front wall 32 of the member 14, and thus seal the space beneath the tuyères against leakage of air into the ash pit.

The tuyère banks 10 are built up of tuyère plates 35 of uniform dimensions and superimposed one upon another in stepped relation to form an inclined fuel supporting surface. Special base tuyère blocks 36 are, however, preferably employed at the rear or lower end of the tuyère banks. These base tuyère blocks 36 have a greater vertical dimension than the tuyère plates 35, being from two to four times the thickness of the tuyère plates, and are of such conformation as to present no protruding edges which may be subject to ready deterioration or burning out. As shown, each tuyère block 36 has in its upwardly presented surface a plane portion upon which the lowermost tuyère plate rests and exposed sloping faces receding downwardly and rearwardly from the surface of contact of the tuyère block with the lowermost tuyère plate 35. The rear end face of the tuyère block 36 also slopes downwardly from the rearmost edge of the tuyère plate superimposed thereon. The base tuyère block 36 further coacts with the flanges 24 of the side plates 19 and the dead plates 30 to anchor the tuyère bank securely in place at its lower end. The base tuyère block 36 is preferably hollow and is cooled 35 interiorly by the flow of air passing to the tuyère openings.

The discharge mechanism 16, herein illustrated, comprises an oscillating dump grate 40, preferably sectional and in width equal 40 to the distance between the center lines of the tuyères, carried upon a shaft 41 which is supported in brackets 42 protruding from the rear wall 32 of the member 14. Air is supplied to the hollow grate sections 40 45 through registering ports 44 and from the grate to the residual fuel thereon through ports 45.

In the arrangement illustrated, the tuyère rows 10 and the bottoms of the retorts 11 overhang the dump grate and extend rearwardly of the side walls 19 which serve in cooperation with the front wall 32 of the member 14 to support these overhanging structures. The dead plates 30 extend the 55 width of the stoker furnace and serve as foundation plates upon which the retort tuyères 25 and the tuyères 35 and 36 of the tuyère banks 10 are disposed.

In operation, fuel is fed into the several 60 retorts from the hoppers 14 by means of the reciprocating rams 15. The fuel entering the furnace retorts spreads out over the tuyère banks 10 and travels downwardly toward the rear of the grate. The retorts 65 by reason of their decreasing depth cause

the coked fuel therein, as it travels toward the rear of the grate, to be gradually raised into the zone of active combustion. The rear, shallow portions of the retorts 10, in which the retort tuyères 25 are situated, 70 are defined at the sides by the base tuyère blocks 36 and the lowermost tuyères 35. The peculiar conformation of the base tuyère blocks 36 produces laterally expanding troughs at the rearmost portions of the 75 grate for the fuel traveling downwardly through the retorts and permits the air rearwardly discharged from the retort tuyères to promote more complete combustion of the rearmost portion of the fuel bed without subjecting the lower tuyères of the tuyère banks 10 to destructive heat action.

As illustrated, the underfeed grate overhangs the discharge or dump grates and, by virtue of the cooperative action the receding base tuyère blocks 36 and the shallow retorts provided with the retort tuyères, the residuum of the fuel passes into the dump grates in a substantially uniformly even bed with a minimum of unconsumed fuel in the residuum.

Experience has shown that the underfeed stoker hereinabove described is enabled to burn satisfactorily the large quantities of fuel necessary to supply the heat energy to boilers at peak loads and that, at the over-load rating at which the generating units of public utility power plants are frequently operated, the combustion efficiency of this stoker is superior to that attained by stokers having extended overfeed sections.

In the modified form illustrated in Fig. 7, I show the rear end of a retort of an underfeed stoker furnace, in which the lower end of the retort bottom consists of four tuyère plates. The construction is essentially the same as that described above, the same reference numerals indicating like parts and a detailed description thereof is deemed to be unnecessary. Structures of this character are specially adapted to stokers of considerable length and it is to be understood that more than four retort tuyères may be employed at the lower end of the retorts, if desired.

This application is a continuation-in-part of my application Serial No. 396,378, filed July 15, 1920.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claim.

What I claim is:

In an underfeed stoker, an inclined grate

comprising a plurality of inclined banks of tuyères and retorts between adjacent tuyère banks, each retort being of generally decreasing depth from front to rear, the retort sides at the rear shallow end of the retort flaring upwardly and rearwardly, the bottom of each retort being formed at its rear shallow end of a plurality of tuyère blocks superimposed one on the other in stepped relation and having tuyère openings for discharging air rearwardly into the retort. 10

In testimony whereof, I have hereunto subscribed my name this 5th day of April, 1923.

ROBERT A. FORESMAN.
